UNITED STATES PATENT OFFICE

EARLE J. R. BEATTEY, OF EDGEWOOD, RHODE ISLAND, ASSIGNOR TO UNIVERSAL
OPTICAL CORPORATION, OF PROVIDENCE, RHODE ISLAND, A CORPORATION OF
RHODE ISLAND

DESIGN FOR A BRIDGE FOR AN EYEGLASS MOUNTING

Application filed December 27, 1929. Serial No. 33,956. Term of patent 14 years.

To all whom it may concern:

Be it known that I, EARLE J. R. BEATTEY, a citizen of the United States of America, residing in Edgewood, county of Providence,

State of Rhode Island, have invented a new, original, and ornamental Design for a Bridge for an Eyeglass Mounting, of which the following is a specification, reference being had to the accompanying drawing, forming a part thereof.

Fig. 1 is a face view and Fig. 2 is a top

view of a bridge for an eyeglass mounting, showing my new design.

I claim:

The ornamental design for a bridge for an eyeglass mounting, substantially as shown.

EARLE J. R. BEATTEY.
